SELF ALIGNING KEY GUIDE FOR LOCKS

Filed March 26, 1927

FIG. 1.

FIG. 3.

FIG. 2.

Inventor

Henry H. Hanton
By Dowell & Dowell
his Attorney

UNITED STATES PATENT OFFICE.

HENRY H. HANTON, OF LANCASTER, PENNSYLVANIA.

SELF-ALIGNING KEY GUIDE FOR LOCKS.

Application filed March 26, 1927. Serial No. 178,792.

This invention relates to locks, and more particularly to means employed for guiding a key into position for locking or unlocking engagement with the locking mechanism contained in a suitable case or enclosure having an opening therein for the insertion of a key.

Locks as heretofore constructed with a rotatable key-guide are subject to objection because of the trouble, annoyance and inconvenience occasioned by the necessity for turning the guide into proper position for inserting the key to unlock the locking mechanism, as such key-guides are unrestrained against rotation and are liable when a key is withdrawn to be thrown out of alignment with the opening in which the key is inserted for actuating the lock and must be restored to proper position before the key can be inserted.

The objects of my invention are to obviate the foregoing objections to locks with rotatable key-guides as heretofore constructed and to provide a lock with a self-aligning key-guide that will maintain itself in a relatively fixed position under normal conditions in alignment with an opening in which the key is inserted for actuating the locking mechanism and will be automatically restored to normal position when thrown out of alignment in withdrawing the key.

The invention will first be hereinafter more particularly described, with reference to the accompanying drawings, which are to be taken as a part of this specification, and then pointed out in the claims at the end of the description.

In said drawings, Fig. 1 is a side view of a padlock embodying my invention; the case being partly broken away to show the interior construction and the locking mechanism being partly indicated in dotted lines;

Fig. 2 is an end view of the case showing the self-aligning key-guide;

Fig. 3 is a transverse section on a slightly enlarged scale taken on the line 3—3 of Fig. 1; and

Fig. 4 is a detail view partly in section illustrating a broken-away portion of the casing in which the key-guide is housed and encircled by a coiled spring which serves to restore the guide to normal position when thrown out of alignment.

In the illustrated embodiment of my invention it is shown applied to a padlock, but it will be understood of course that my im-

proved self-aligning key-guide may be applied to various kinds of locks other than padlocks; for example, cabinet locks, door locks, locks for trunks, suit cases and bags, and any kind of lock with the customary type of flat key requiring a key-guide through which the key may enter in alignment with an opening in which the key is inserted for actuating the locking mechanism; the key-guide being held normally in position for the insertion of the key and adapted to be automatically restored to normal position when thrown out of alignment.

In said drawings, in which the same reference letters are used to denote corresponding parts in different views, an ordinary padlock is shown having a U-shaped shackle inserted in holes in the case which is made in two parts or upper and lower members A

and A¹ having marginal flanges a and a¹ respectively, adapted to rest one upon the other, as shown, and secured together by bolts or rivets in a manner well known to manufacturers and users of locks; said case containing suitable locking mechanism for engagement with one or both limbs of the shackle so as to lock and hold the shackle firmly locked to the case until released by means of a key adapted to actuate the locking mechanism to unlock the shackle. The locking mechanism as indicated in dotted lines, may include any suitable sliding dog or pawl such as commonly used in locks of the kind shown, adapted to engage a notch or notches in a limb or limbs of the shackle B and to be thrown out of engagement therewith for unlocking the shackle by means of a key inserted in the key-guide C so as to enter an aligned slot or socket in a bushing b¹ which is rotatably secured within the casing and has formed thereon means for engagement with the dog so that by partial rotation of the bushing the dog will be moved out of engagement with the shackle; spring-actuated means of the kind usually employed being provided to resist rotation of the bushing and movement of the dog and to return the same to normal position for locking engagement of the dog with the shackle when the key is withdrawn. In the form indicated in dotted lines there are oppositely movable dogs b each adapted to engage a notch in the adjacent limb of the shackle and each having a recess to receive a vertically disposed oblong projection b² on the bushing b¹ so that when the bushing is turned by the

key inserted in the key-guide C so as to enter an aligned slot or socket in a bushing b¹ which is rotatably secured within the casing and has formed thereon means for engagement with the dog so that by partial rotation of the bushing the dog will be moved out of engagement with the shackle; spring-actuated means of the kind usually employed being provided to resist rotation of the bushing and movement of the dog and to return the same to normal position for locking engagement of the dog with the shackle when the key is withdrawn. In the form indicated in dotted lines there are oppositely movable dogs b each adapted to engage a notch in the adjacent limb of the shackle and each having a recess to receive a vertically disposed oblong projection b² on the bushing b¹ so that when the bushing is turned by the

key inserted in the key-guide C so as to enter an aligned slot or socket in a bushing b¹ which is rotatably secured within the casing and has formed thereon means for engagement with the dog so that by partial rotation of the bushing the dog will be moved out of engagement with the shackle; spring-actuated means of the kind usually employed being provided to resist rotation of the bushing and movement of the dog and to return the same to normal position for locking engagement of the dog with the shackle when the key is withdrawn. In the form indicated in dotted lines there are oppositely movable dogs b each adapted to engage a notch in the adjacent limb of the shackle and each having a recess to receive a vertically disposed oblong projection b² on the bushing b¹ so that when the bushing is turned by the

key inserted in the key-guide C so as to enter an aligned slot or socket in a bushing b¹ which is rotatably secured within the casing and has formed thereon means for engagement with the dog so that by partial rotation of the bushing the dog will be moved out of engagement with the shackle; spring-actuated means of the kind usually employed being provided to resist rotation of the bushing and movement of the dog and to return the same to normal position for locking engagement of the dog with the shackle when the key is withdrawn. In the form indicated in dotted lines there are oppositely movable dogs b each adapted to engage a notch in the adjacent limb of the shackle and each having a recess to receive a vertically disposed oblong projection b² on the bushing b¹ so that when the bushing is turned by the

key against the resistance of a spring acting thereon, the projection b^2 will exert a cam-like action on the sliding dogs and move them out of engagement with the shackle and 5 when the key is withdrawn the bushing will be caused to rotate in the opposite direction and return the dogs into locking engagement with the shackle; suitable means being provided within the casing to limit the 10 rotation of the bushing in a backward direction and arrest its movement the instant the slot in the bushing is brought into alignment with the key-opening through the key-guide. The locking mechanism may be of 15 the form indicated, or any suitable form such as commonly used in locks of various kinds may be employed, and as the locking mechanism per se forms no part of my present invention, further description thereof appears to be unnecessary. As shown, the key-guide C, through which the key enters for 20 the purpose of holding the key in position when being passed in and out of the lock and which forms the axis or bearing on which 25 the key revolves during the operation of unlocking the lock, is in the form of a circular body rotatably confined and housed within the case A— A^1 , between the rear end wall thereof and the ends of vertically disposed 30 longitudinal bars or flanges a^2 and a^3 formed on or secured to the inner sides of the casting members A and A^1 , respectively, at one side of the key-guide or a centrally disposed opening through which the key passes into 35 the slot or socket in the bushing b^1 ; similar vertically disposed flanges or equivalent means being provided at the other side of said key-guide or centrally disposed opening so as in effect to provide a housing for such 40 means as are commonly employed in co-operative relation to the key to prevent the lock from being unlocked by a key unadapted for co-operation with the combination used to open the lock. The rotatable 45 body or key-guide C has an oblong slot c therethrough adapted to receive the customary type of flat key; protuberances or projections c^1 being formed on opposite sides of the slot c and adapted to fit into grooves 50 in a key having longitudinal grooves spaced apart so as to permit the projections to enter the grooves when the key is inserted for unlocking the lock. Said body also has a recess c^2 of arcuate form in its periphery and 55 is encircled by a coiled spring E which has its inner end bent substantially at right angles thereto so as to provide a tooth or projection which is inserted in a hole in the circular body co-incident with the recess c^2 therein, while the free end e of the spring 60 impinges against the inner side of the casing so as to resist rotation of said body and 65 yieldingly hold it with the key-opening therethrough normally in alignment with the slot in the bushing b^1 , so that when the key-

guide is thrown out of alignment, as usually occurs when the key is withdrawn, the spring will automatically restore the key-guide to normal position. To limit the rotation of the circular body of the key-guide in a backward direction induced by the recoil of the spring when said body is thrown out of normal position, the flange a^3 is extended slightly past the end of the flange a^2 into the arcuate recess c^2 in said circular body, so as to 70 provide a shoulder or abutment a^4 with which the shoulder formed by the recess in said circular body will contact when said body is rotated by the recoil of the spring and prevent rotary movement thereof beyond the point at which the key-opening is 75 brought into aligned position.

While I preferably employ a coiled spring for holding the key-guide in normal position for convenience in assembling the parts and 80 because of its adaptability to locks with key-guides of the form shown, springs of a different type may be used, and various changes may be made in the details and arrangement of parts without departing from the spirit and scope of my invention, and I 85 therefore do not desire to be limited in the appended claims to the specific construction 90 illustrated and described.

The advantages of my improvement over 95 key-guides as heretofore constructed are obvious. In using rotatable key-guides as heretofore constructed, when the key is withdrawn the key-guide is usually slightly rotated and will remain with the slot therein at an angle to the slot or opening provided for the insertion of the key to unlock the locking mechanism, whereas in using my improvement, the key-guide being arranged and held normally with the key-opening or 100 slot therein in alignment with the opening in which the key is inserted for actuating the locking mechanism, a suitable key may be inserted without the annoyance and inconvenience incident to the necessity for 105 turning the key-guide as heretofore constructed so as to bring the key-opening or slot therein into proper alignment with the opening in the locking mechanism.

Having thus described my invention, what 110 I claim as new and desire to secure by Letters Patent of the United States is:

1. In combination with a lock containing mechanism adapted to be actuated by means of a key inserted in an opening therein, a 115 rotatable key-guide having a slot extending therethrough for inserting a key; said slot being arranged in alignment with said opening, and means for yieldingly holding the slot in said guide normally in alignment with said opening; said means serving to automatically restore the guide to normal 120 position when thrown out of alignment.

2. In combination with a lock containing 125 key-actuated mechanism, a rotatable key- 130

- guide having the opening therethrough for inserting a key arranged in alignment with an opening in which the key is inserted for actuating said mechanism, and means for 5 yieldingly holding said key-guide in a relatively fixed position; said means serving to automatically restore the key-guide to normal position when thrown out of alignment.
3. In a lock, the combination with locking 10 mechanism, of a rotatable key-guide having a key-opening therein arranged normally in alignment with an opening in which the key is inserted for actuating said mechanism to lock or unlock the same, and means 15 for yieldingly holding said key-guide in aligned position, said means serving to return the guide to normal position when thrown out of alignment.
4. A lock comprising a case containing 20 suitable locking mechanism adapted to be actuated by a key for locking and unlocking the same, and a rotatable body having an oblong slot therethrough for inserting and guiding a key to lock or unlock said mechanism; said slot being normally in alignment with an opening in which the key is inserted for actuating said mechanism, and means for yieldingly holding said body in a 25 relatively fixed position; said means serving 30 to return said body to normal position when thrown out of such position.
5. A padlock comprising a case enclosing 35 key-actuated locking mechanism and having spaced holes therein in which is inserted a slidable shackle adapted to releasably engage said mechanism, a rotatable key-guide having a key-opening therein arranged normally in alignment with an opening in which the key is inserted for actuating said mechanism, and means for automatically restoring 40 said key-guide to normal position when the key-opening therein is thrown out of alignment.
6. A padlock comprising a case enclosing 45 suitable locking mechanism and having a slidable shackle inserted in holes therein and releasably engaging said mechanism, a rotatable body having an oblong slot therein for inserting and guiding a key; said slot being 50 arranged normally in alignment with an opening in which the key is inserted for actuating said mechanism, and means for yieldingly holding said body in normal position; said means serving to automatically restore said body to normal position when thrown out of such position.
7. In a lock, the combination with locking 55 mechanism, of a rotatable key-guide having a key-opening therein arranged normally in alignment with an opening in which the key is inserted for actuating said mechanism to lock or unlock the same, and means for yieldingly holding said key-guide in aligned position and returning it to the latter position when thrown out of alignment; said means 60 including a spring which serves to yieldingly resist movement in one direction and a stop for limiting the return movement to aligned position.
8. A padlock comprising a case containing 65 suitable locking mechanism, including a rotatable device and means actuated thereby for locking and unlocking a shackle slidably fitted in openings in the case, an independently rotatable body having an oblong slot 70 therein for inserting and guiding a key therethrough; said rotatable device having a recess therein adapted in normal position to receive the end-portion of a key protruding thereinto through the slot in said body, and means for yieldingly holding said body with the slot therein normally in alignment with the recess in said device; said means being 75 adapted to return said body and device to normal position when thrown out of alignment.
9. A padlock comprising a case containing 80 suitable locking mechanism, including a rotatable device and means actuated thereby for locking and unlocking a shackle slidably 85 fitted in openings in the case, an independently rotatable body having an oblong slot therein for inserting and guiding a key therethrough; said rotatable device having a recess therein adapted in normal position to receive the end-portion of a key protruding thereinto through the slot in said body, and means for yieldingly holding said device and body with said slot and recess normally in 90 alignment and returning them to normal 95 position when thrown out of alignment.

In testimony whereof I affix my signature.

HENRY H. HANTON.
